(57) **CLAIM**

The ornamental design for a sensor housing assembly for hydraulic hose, as shown and described.

DESCRIPTION

FIG. 1 is a perspective view of a sensor housing assembly for hydraulic hose showing my new design.

FIG. 2 is an alternate perspective view of the sensor housing assembly for hydraulic hose of FIG. 1.

FIG. 3 is a left elevation view of the sensor housing assembly for hydraulic hose of FIG. 1.

FIG. 4 is a right elevation view of the sensor housing assembly for hydraulic hose of FIG. 1.

FIG. 5 is a bottom plan view of the sensor housing assembly for hydraulic hose of FIG. 1.

FIG. 6 is a top plan view of the sensor housing assembly for hydraulic hose of FIG. 1.

FIG. 7 is a back elevation view of the sensor housing assembly for hydraulic hose of FIG. 1; and,

FIG. 8 is a front elevation view of the sensor housing assembly for hydraulic hose of FIG. 1.

The broken lines illustrate portions of the sensor housing assembly for hydraulic hose which form no part of the claimed design.
